United States Patent Office.

B. C. YOUNG, OF BOSTON, MASSACHUSETTS.

Letters Patent No. 69,528, dated October 1, 1867.

IMPROVEMENTS IN BOOTS AND SHOES.

The Schedule referred to in these Letters Patent and making part of the same.

TO ALL WHOM IT MAY CONCERN:

Be it known that I, B. C. Young, of Boston, in the county of Suffolk, and State of Massachusetts, have invented an Improvement in Boots and Shoes; and I do hereby declare that the following, taken in connection with the drawings which accompany and form part of this specification, is a description of my invention sufficient to enable those skilled in the art to practise it.

In those boots and shoes which are drawn upon the feet by pulling upon loops or straps fixed thereto, the presence of such loops or straps is at all times objectionable, excepting for the purpose of putting on the boot or shoe, the strap being in itself unsightly, the fastenings by which it is attached to the boot rendering the boot-leg rigid at the point of attachment, and causing it to chafe the leg, and the material of which the loop is made often breaking when it is pulled upon, leaving no provision for drawing on the boot.

To remedy these defects, I apply at the top and to the opposite sides of the boot or shoe-leg or upper, or to the back and front thereof, buttons or knobs, firmly riveted, stitched, or otherwise secured to the leg or upper, these devices being of such form and so disposed that by placing the fore-finger of one hand under one of them, and carrying the thumb to the inside of the boot opposite thereto, and then pinching the boot, (doing the same thing with the other hand at the opposite button on the same boot,) the boot may be thus readily drawn upon the foot, the protuberances made by the knobs or buttons enabling a firm hold to be maintained or preventing the fingers from slipping. It is in such application of buttons or analogous devices to boot or shoe-legs or uppers that my invention consists. The drawings represent a Congress boot embodying the invention—

A showing a side view, and B a back view of the same.

a denotes the sole; b the upper; c one of the elastic gores. Upon the front and rear of the upper or leg, at the top thereof, are the buttons d d. In the drawings each button is secured to the leather of the boot by a rivet, but it may be fastened in place by strong stitches or otherwise, the outer part of the button or knob being of form and in position to be freely seized by the fingers.

It will readily be seen that the use of these devices obviates entirely the objections attending the employment of leather or webbing-straps or loops, the buttons being not only strong in themselves, but being also not liable to become detached by strain upon them. Moreover, they are ornamental in appearance, and do not project in against the leg of the wearer, and are never in position to cause any annoyance in walking. They are less expensive than straps, and never require mending.

I do not confine my invention to any particular style of boots or shoes, although it is particularly applicable to Congress or to long-leg boots.

I claim a boot having buttons or knobs securely fastened to and projecting from the opposite outer surfaces of the leg, near the top thereof, or in such position that by applying a fore-finger under each button or knob, and a thumb to the inner surface opposite said button or knob, the boot may be securely grasped to pull it on the foot, substantially as set forth.

B. C. YOUNG.
